United States Patent Office.

MICHAEL LOUGHREN, OF PITTSBURG, PENNSYLVANIA.

Letters Patent No. 72,512, dated December 24, 1867.

IMPROVED MACHINE FOR ROLLING CLEVIS-BLANKS.

The Schedule referred to in these Letters Patent and making part of the same.

TO ALL WHOM IT MAY CONCERN:

Be it known that I, MICHAEL LOUGHREN, of the city of Pittsburg, in the county of Allegheny, and State of Pennsylvania, have invented a new and useful Improvement in Rolls for Making Clevis-Blanks; and I do hereby declare the following to be a full, clear, and exact description thereof, reference being had to the accompanying drawings, making a part of this specification, in which—

Figure 1 is a front view of a pair of my improved rolls, and

Figure 2 is a cross-section, formed by a plane passing vertically through the rolls in the line $z z$, fig. 1, and also illustrating their mode of operating, by showing the position of a bar while passing through between the rolls.

Like letters of reference indicate like parts.

The nature of my invention consists in the construction of cylindrical rolls with an arrangement of grooves and notches in their outer cylindrical surfaces, whereby a rod or bar of iron, having a cross-section other than circular or square, will, when passed through between such rolls, be rolled into the shape required for clevis-blanks, from which to manufacture plough and other similar clevises. The distinguishing characteristic of such clevises is the peculiar shape of the head which fits over the end of the plough-beam. Such head is usually formed with one or more notches, in any one of which to place the ring by which the swingle-tree or double-trees are connected to the plough, so that, by setting the ring in a higher or lower notch, the depth of the furrow is regulated. Such clevises have heretofore been manufactured usually by forging and by hand. By my invention, I propose to roll clevis-blanks of such shape that clevises can be rapidly and easily made therefrom, nothing, in fact, being required to complete the clevis, after the blanks are rolled, except cutting them apart, and bending and punching.

To enable others skilled in the art to make and use my invention, I will proceed to describe its construction and mode of operation.

The rolls $a a'$ are of any known material ordinarily used for such purposes, cylindrical in form, except that one, a' , has a flattened groove, b , extending entirely around it; and the other, a , has one, two, or more, short grooves, c , running across its surface at right angles, or nearly so, to the line of its axis. In the bottom of each of such grooves c are one or more notches, i , of depth and size such as to form the projecting lips e of the clevis-blank as the bar d is passed through between the rolls $a a'$. The bead f is, at the same time, shaped by the groove c , and the strap g of the blank, in the groove b of the roll a' , and between the bottom of it and the cylindrical face of its opposite roll, a . The rolls $a a'$ are set in proper journals, and operated by gear-wheels, $h h'$, or by any other equivalent well-known device.

At the proper point for inserting the bar d between the rolls $a a'$, and so that it will strike the grooves and notches described, I place a guide, consisting of a mortised block, attached to the frame m , which carries the rolls $a a'$, or, more commonly, as shown in the drawings, of two guiding-plates or blocks, $n n$, concave on their inner face, so as to leave an aperture, l , such guiding-blocks being set in and held by the cross-bar o , attached to the frame m . I commonly fit the guiding-blocks n to or in the cross-bar o in such way that they can readily be removed and other guides inserted, by which a larger or smaller aperture, l , is secured at pleasure. Through such aperture l I feed a bar or rod of iron of any desirable shape other than those the cross-sections of which are either circular or square. Such bar, when passing through the rolls, should have the longest axis of its cross-section at right angles, or nearly so, to the direction of the axes of the rolls $a a'$. I usually prefer a rod or bar of elliptical, lozenge-shaped, or rectangular cross-section, though bars of other forms may be rolled, as above stated. The aperture l should correspond so far in shape to the bar d that the latter, while passing through between the rolls $a a'$, will be retained in the position indicated, with the longest axis of its cross-section at right angles to the axes of the rolls. Such bar d , passing through between the rolls $a a'$, will, by the lower roll, a' , and so much of the cylindrical surface of the upper roll, a , as lies between the extremities of the grooves c , be rolled into the straps g of the blank, the bead f and lips e being formed in the grooves c and notches i , respectively, in like manner, as already described. The bar thus rolled is then cut into separate blanks, the points of cutting being always in the strap g , and at such distances from the clevis-head, formed in the grooves c , as will leave an arm on either side of such head, of any desirable length, to be bent over or back.

into an ox-bow or clevis shape, to fit the end of the plough-beam. The requisite bolt-holes are then punched, and the clevis otherwise finished at pleasure. By this process, I make clevis-blanks from which to make clevises for not only ploughs, but also cultivators, harrows, and other similar agricultural implements with which clevises of such shape are either necessary or desirable.

As shown in the drawings, one of the grooves *c* has two notches *i*, and the other but one. I do not limit myself to any particular number, though usually, for convenience' sake, I make the roll *a* with the same number of notches *i* in each of its grooves *c*; nor do I limit myself to any particular number of grooves *c* in the roll *a*, as there may be one, two, or more, according to the length of the circumference of the roll relative to the length of the straps *f* of the blank to be rolled.

In order to give the clevis a better shape, or facilitate the finishing of it, I usually make the groove *b* with a concave transverse face, or shallower at its edges, and bevelled off toward the middle; but, though desirable, I do not consider the groove *b* essential to the successful operation of my invention. The roll *a'* may be made cylindrical throughout, its mode of operation still remaining substantially the same.

What I claim as my invention, and desire to secure by Letters Patent, is—

One or more grooves *c* in the periphery of one of a pair of cylindrical rolls, with one or more notches or depressions *i* in the bottom of each such groove, all of the form substantially as described, in combination with the notched or mortised guides *n*, for the purposes above set forth.

In testimony whereof, I, the said MICHAEL LOUGHREAN, have hereunto set my hand, in presence of—

MICHAEL LOUGHREAN.
